UNITED STATES PATENT OFFICE.

NORBERT FRANK, OF FORST, LUSATIA, GERMANY.

FEEDING DEVICE FOR HORSEHAIR-SPINNING MACHINES.

1,095,098.

Specification of Letters Patent. Patented Apr. 28, 1914.

Application filed April 8, 1912. Serial No. 689,368.

To all whom it may concern:

Be it known that I, NORBERT FRANK, a subject of the King of Bavaria, residing at Forst, in Lusatia, Germany, have invented

5 certain new and useful Improvements in Feeding Devices for Horsehair-Spinning Machines; and I do hereby declare the following to be a full, clear, and exact description of the invention, such as will enable others skilled in the art to which it appertains to

10 make and use the same, reference being had to the accompanying drawings, and to letters or figures of reference marked thereon, which form a part of this specification.

15 This invention relates to means for withdrawing one or more hairs from a bundle of horse-hair and feeding the same to a feeding device for spinning or other machines.

It has heretofore been proposed to remove 20 single hairs from a bundle of horse-hair by means of fingers mounted on a continuously rotating disk, so that the ends of said fingers describe the arc of a small circle through the bundle, with the result that the action 25 was not certain, and that tangling of the hairs often resulted, so that for rapid operation such a mechanism was entirely unsuitable. In the present structure the fingers have the movement of a flat arc, *i. e.* an 30 arc of small curvature, and their action is certain, thereby attaining a uniform feed.

Referring to the drawings, in which like parts are similarly designated Figure 1 is 35 an elevation, partly in section, of one form of the device. Fig. 2 is a plan. Fig. 3 is a view similar to Fig. 1 showing the position of the fingers after having released the hair or hairs that have been withdrawn from the bundle. Fig. 4 is a view similar to Fig. 1 40 of a modification. Fig. 5 is a plan of Fig. 4. Fig. 6 illustrates other positions of the fingers shown in Fig. 4. Fig. 7 is a side elevation of a further modification. Fig. 8 is a plan thereof. Fig. 9 shows a modification 45 of Fig. 5.

Referring to Figs. 1 to 3, the horse-hair having its end *n* projecting from the bottom of an inclined trough *l* is held in proper relation to the fingers for pulling the hair 50 from the bundle. This trough is cut off at an angle at 25 and has a slot 26 through which passes a cord or other flexible binder 55 that is connected to means for placing a yielding pressure on the hair. This means, in the present instance, comprises a spring 28 connected to hook 29 on the end of a

screw bolt *m* that is longitudinally adjustable in the bent end of a bracket 30 by means of a thumbnut 31, or otherwise. This bracket 30 is secured to and supports the 60 trough *l*.

Extending from the frame *F* of the machine is a standard 32 having a threaded bolt 33 at its upper end, provided with two nuts 34 which hold the bracket 30, and 65 trough *l* at the proper height, and also serve as means for adjusting the height of the trough and ends of the hair with respect to the fingers.

Just below the portion 25 of the trough *l* 70 is a pair of curved guide plates *i*, *i'* secured to the frame *F* by the nuts *i*' and separated from one another to form a slot *k* having an enlarged entrance *k'*, Fig. 2. Back of these curved guide plates is a pair of spaced vertical guides *r*, *r'* secured to the frame *F*.

Mounted in the frame *F* is a shaft 35 carrying a double cone roller *h* (apices juxtaposed) and coöperating therewith and in frictional driving relation thereto is a 80 complementary double cone roller *h'*, (bases juxtaposed) whose shaft 36 is mounted in arms *p* pivoted to the frame *F* at 37. The roller *h'* is yieldingly held against roller *h* by springs *q* connected at one end to the 85 arms and at their other ends to a screw or other fastening in the frame *F*.

The shaft 35 carries a gear wheel *o* that meshes with a similar gear wheel *a* on shaft 38 mounted in a bearing 39 on a bracket 40. 90 This shaft carries a crank disk *b* having a crank pin *c* on which are mounted the spring fingers *d'*. The fingers are preferably made of spring metal welded together or otherwise united at their rear ends *d* where the pin *c* 95 passes through them. These fingers are also provided with a slot *g* through which passes a stationary guide pin *f'* in standard *f* secured to bracket 40. The forward ends of the fingers *d'* are bent toward one another 100 at *e*, and are vertically guided under all conditions of operation between the spaced vertical guides *r*, *r'*.

Slidable on rails 41 in the frame *F* is a block *s* or the like, carrying a funnel-shaped 105 delivery device *t*. The delivery device can, therefore, be moved beneath the nip of the rolls *h* and *h'* as circumstances may require.

Power is preferably, but not necessarily applied to the shaft 35 in any suitable manner, and motion is transmitted therefrom by gear wheels *o* and *a* to shaft 38, to rotate 110

the crank disk 6. As this disk rotates the fingers d' pivot and slide on the stationary pin f' and are moved into the enlarged entrance h' of slot h . The slot h is dimensioned relatively to the ends of the fingers to press them together to seize a hair from the projecting ends in the bundle lying against the guides i . The fingers move upwardly toward the bundle from the full line position Fig. 1, to the dotted line position Fig. 1, whereupon the ends e move downward beyond the guides i until the end of the hair has been seized by the rolls h h' when they move inwardly through the slot h Fig. 3, and spring apart, the guides r , r' limiting the lateral movement of the ends of the arms. The rolls deliver the hair to the funnel-shaped guide t and to the spinning machine.

In Figs. 4 to 7 I have shown the fingers movable in horizontal parallel lines instead of inclined, and the projecting ends of the hairs 11 substantially vertical. The rolls are indicated at h and h' , the roll h' being provided with a belt or chain wheel 42 driving by belt or chain 43 a wheel 44 on a shaft 45 mounted in a bracket 46. Shaft 45 carries a pinion 47 meshing with gear wheels 48 and 49, one on each side thereof. These gear wheels 48 and 49 are on shafts 9 and 9' in bracket 46. The shafts 9 and 9' carry crank disks 6 and 6' respectively having crank pins 5 and 5'.

The fingers 2 are provided with two slots 4 and 4' in which enter the crank pins 5 and 5' respectively. Each finger is provided with a stop 7 and 7' adapted to be urged against the vertical guides 3 and 3'. These guides 3 and 3' are separated from one another to form a slot 3'' having an enlarged entrance. A spring 10 connected at one end to 9 and at the other end to a pin 8 in the rear end of the fingers urges the stops 7, 7' against the guides 3, 3'. The slots 4 and 4' are of a length about equal to the eccentricity of the crank pins 5 and 5'. In this construction the fingers 2 are maintained horizontal and seize a hair from the bundle 11, draw it down vertically toward the rolls h and h' and then move in a curved path upwardly to their initial position. The path of the ends of the fingers is indicated at P in dotted lines. This path is described by reason of the crank pins sliding in slots 4 and 4' during the first half rotation of the crank disks 6 and 6', the spring 10 maintaining the stops 7 and 7' against the guides 3, 3', the pins 5 and 5' carrying the fingers down while urged by the spring 10. During the second half of the rotation of the disks the pins engage the right hand ends of the slots, Fig. 6, and effect the upward movement of the ends of the fingers in a curved path back of the guides 3, 3'.

In Figs. 7 and 8 I have illustrated the fin-

gers 2 as moving in inclined lines with respect to the guides 3, 3'. The ends e of the fingers pass between the guides and the anti-friction rollers 18, acting in the manner of the stops 7, 7', prevent the fingers from being projected too far beyond the guides 3, 3' by their urging spring 14. This spring is a leaf spring engaging the rear end of the fingers 2. The fingers are provided with two slots 13 and 17 in which enter the pins 12 and 16. The pin 16 is on the crank disk 15 on shaft 50 that carries the gear wheel 22 and belt or sprocket wheel 51. The gear wheel 22 meshes with the gear wheel 22' on shaft 52 that carries a cam 19 on which, at its center, is pin 12. The rear end of the fingers carries a roller 20 in the path of the cam 19. The fingers are slideable in relation to pin 12 and pivot about it, while the pin 16 effects the swing of these fingers on 12 as a pivot. The spring 14 urges the fingers forward during one half a rotation of crank disk 15 until the ends e of the fingers execute their movement from their upper to their lower position, after which cam 19 engages roller 20 to move the fingers from between the guides 3, 3' during their upward movement.

In the modification shown in Fig. 9 the swing of the fingers instead of being effected directly by the crank pin 16, Fig. 7, is accomplished by a crank disk 23, having a crank pin 24 and connecting rod 25 pivotally connected to the fingers at 25'.

It will be noted that the horse hair in all the forms shown is held in a stationary bundle, and the direction of movement of the fingers when seizing a hair is substantially perpendicular to the hair at the point of engagement thereof by the fingers. It is also of advantage to have the fingers when passing through the bundle of hair (operative movement) describe as flat an arc as possible, and preferably to draw the hair therefrom in as near a straight line as possible, after which the idle movement may take place in any desired path.

I claim:

1. The combination with means for holding a bundle of hairs; of fingers made of spring metal normally separated at their forward ends, stationary guides in close proximity to said bundles adapted to engage the forward ends of said fingers, a crank on which the fingers are pivotally mounted, and a pivot between the crank and gripping end of the fingers on which the fingers are slideably mounted, said crank and pivot co-operating to move the forward ends of the fingers along the guide in a closed path.

2. In a machine of the character described, the combination with a pair of guides, spring fingers co-operating with and closed by said guides, stops on the fingers to limit their movement between the guides, a crank

to swing the fingers, a pin about which the fingers pivot, said fingers being in sliding relation to the pivot, and means to urge the stops against the guides, whereby the ends 5 of said fingers will have substantially rectilinear movement for one half of their path of movement and curvilinear movement for the other half thereof.

3. In a machine of the character described, 10 the combination with a pair of guides; of spring fingers, stops at their forward ends, a spring to urge the fingers between the guides and the stops against the guides, a crank pin engaging in a slot in the fingers, 15 and a second pin engaging in a second slot in the fingers, said pins effecting the movement of the fingers in relation to the guides.

4. In a device of the class described, in combination a fixed holder adapted to contain 20 the fibers, a pair of guides at the end of the holder, a pair of rotatable members mounted contiguous to the guides, spring fingers slidably mounted on the rotatable members and adapted to be projected between 25 the guides by the rotation of said members, stops on the fingers to limit their movement between the guides, and yielding means to hold the stops against the guides, whereby the ends of said fingers will have 30 rectilinear movement away from the holder and curvilinear movement toward the latter.

5. In a device of the class described, in combination a fixed holder adapted to contain the fibers, a pair of guides at the end of the holder, a pair of spring fingers, means 35 to actuate the fingers in parallel longitudinal lines toward and from the holder, stops on the fingers arranged to engage the guides to limit the forward movement of the fingers, and yielding means to hold the stops 40 against the guides whereby said fingers are moved longitudinally of the guides by said actuating means.

6. In a device of the class described, in combination, a fixed container for the fibers, 45 a pair of gears mounted adjacent the container, an intermediate gear between said gears meshing therewith, crank pins on said gears, spring fingers having longitudinal slots through which said pins project, guides 50 mounted between the fingers and container, a spring to urge the fingers between the guides and stops on the fingers adapted to engage the guides, for the purpose specified.

In testimony that I claim the foregoing as 55 my invention, I have signed my name in presence of two subscribing witnesses.

NORBERT FRANK.
